UNITED STATES PATENT OFFICE

STORRS M. BISHOP, OF SCHENECTADY, NEW YORK.

POWER-SHOVEL.

1,103,476.

Specification of Letters Patent. Patented July 14, 1914.

Application filed May 19, 1911. Serial No. 628,160.

To all whom it may concern:

Be it known that I, Storrs M. Bishop, a citizen of the United States of America, residing at the city of Schenectady, in the county of Schenectady and State of New York, have invented certain new and useful Improvements in Power-Shovels, of which the following is a specification.

My invention relates to power shovels, and the object of my invention is to provide a means for mounting a shovel in connection with a carriage adapted to ride along a boom under the influence of an engine or counterweights, if desired; together with such elements and combinations as are hereinafter more particularly set forth and claimed. I accomplish these objects by means of the mechanism illustrated in the accompanying drawings, in which:

Figure 1 is a side elevation. Fig. 2 is a cross section of the carriage and boom along the lines X—X on Fig. 3. Fig. 3 is a section through the carriage and boom along the lines Y—Y on Fig. 2. Fig. 4 is a side elevation of a modified form.

Similar letters refer to similar parts throughout the several views.

A, is a suitable mast or other support, and B, is a boom suitably mounted at C, the boom being capable of a rotary motion around C, as a pivot under the direction of the rope or cable, D, which passes over the sheaves, E, in the block, F, attached to the head of the mast, A, and over the sheave, g, in the block, G, attached to the head of the boom, B; also secured preferably at one end to the block, G. It also passes over the sheave, H, near the head of the mast, A, from whence the rope passes to the engine or device used for raising the boom, not shown.

The rope or cable, J, is secured to the block, K, attached to the shovel, L, and also passes over the sheave, L, in the block, K, the sheave, m, in the block, M, attached to the head of the boom, B, passes over the sheave, N, in the boom, B, and the sheave, O, on the side of the mast, A, and passes to the apparatus used for operating same, not shown.

I do not claim any invention in the manner of connecting up the mast, boom and sheaves so far as already referred to and I therefore have given but an outline description of the cables and their connections with the boom, mast and sheaves.

I have shown the boom, B, made up of two parallel frames, P and R. Between these two frames I mount my carriage, S, placing on one face of the frame, P, a suitable bar or plate, T, having flanges, t, t', along the upper and lower edges thereof. Oppositely disposed to the plate, T, on the frame, P, I place the plate, V, on the face of the frame, R, which is provided along the upper edge with the flange, v, and along the lower edge with the flange, v', corresponding to the flanges, t, t', on the plate, T. The flanges, v, and t, form supports for the rollers, 1 and 2, on the carriage, S; and the flanges, v', and t', are engaged by the rollers, 3 and 4, on the carriage as shown in Fig. 2.

The carriage, S, comprises two parallel plates, 5, 6, through which the rod, 7, carrying the rollers, 1, 2, and the rod, 8, carrying the rollers, 3, 4, pass. They are held together by suitable tie rod, 9, and plate, 10, the tie rods being secured by a suitable nut, u, screwing onto the threaded end, U, of the tie rod, 9. The plate, 10, is secured by bolts, 11, passing through the flanges, 12, on the plate, 10, and also through the plates, 5, 6, respectively. Between the plates, 5, 6, I place the movable plates, 13, 14, carrying a series of U-shaped staples, 15, through which the cable, 16, passes and by which it is held in position. Through the plate, 10, I place a series of bolts, 17, which extend from the plate, 14, through the plate, 13, and through the plate, 14, and are held in position by means of the nuts, 18. On the bolts, 17, I place the spiral springs, 19, resting one end against the plate, 13, and the other end against the plate, 10. Between the plates, 13, 14, I place the elliptical springs, 20, one spring preferably at each side of the plates as shown in Fig. 2. To the under side of the plate, 13, as the plate is mounted, I place a series of concave blocks 21, adapted to engage the top of the cable, 16, when held by the U-shaped staples, 15.

Between the plates, 5, 6, and beneath the plate, 14, mounted on a suitable bolt, 9, I pivot the end of the dipper arm, 23. The end of the dipper arm, 23, is formed in an irregular curve, 24, having one side, 25, of the dipper arm higher than the side, 26, making a cam-shaped formation upon that part of the end of the dipper arm which engages the plate, 14, as shown in Fig. 3. The end of the dipper arm is preferably

provided with a metal shoe, 27, held in place by suitable bolts, 28, as shown in Fig. 3.

The shovel, L, is secured by suitable links, 5 p, p, to the sleeved fitting, W, at the end of the dipper arm, 23, being adjusted by means of bolts, w, passing through the links, p, p, into one of the openings, W', in the fitting W, as shown in Fig. 1. In 10 the heel of the shovel, L, I preferably place a door, 30, hinged at 31, near the top of the shovel, holding the door closed by means of a suitable pin, 32, which extends through the collars, 33, on the door and into a suitable opening in the bottom of the shovel or through a catch plate, 34, attached thereto as shown in Fig. 1. The cable, 35, connected with the pin, 32, may be attached to one arm, 36, of the bell crank lever, 37, 15 secured to the dipper arm, 23, or to the shoe, 27, attached thereto. The other arm, 38, on the bell crank lever is adapted to engage with the tripping arm, 39 attached to the plate, 5, as shown in Fig. 1. The dipper arm, 23, may have attached to it the rope, 40, passing over a suitable sheave 41 at the foot of the mast, A, by the operation of which the shovel may be drawn into the desired position for engaging the work after 20 it has been dumped.

The carriage is connected up to cause it to reciprocate along the boom and has attached to each end thereof, at 50 and 51, the opposite ends of the cable, 44. The cable, 35 44, passes over the pulley, 42, on the shaft, 43, near the end of the boom and also over drum, 46, and sheave, 45, near the other end of the boom. This arrangement permits the carriage to move away from the 40 mast toward the free end of the boom during the operation of raising the shovel. To return the carriage after the shovel is dumped I attach a cable, 52, to the carriage at 53, pass the cable, 52, over the sheaves, 45, and 45 54, and secure a weight, 47, to the loose end of the cable, which weight is sufficient to return the carriage to its operative position after the shovel has been dumped.

I show in Fig. 4 a modified form of the 50 means for moving the carriage. The cable, 44, is passed several times around the drum, 46, for the purpose of making a grip thereon. The drum, 46, is operated by means of the cable, 75, passing over the 55 drum, 46, and over the drum, 76, of the hoisting engine, 77. The hoisting engine, 77, may be constructed in any suitable manner.

The operation of my invention is as follows:—The shovel is directed in the usual 60 manner with its toe pointing into the dirt.

Power is applied to the cable, J, which is transmitted through the cable, J, to the forward part of the shovel and the shovel begins to rise. While the shovel is in the ground and in the position for filling, the end of the dipper arm, 23, is in engagement with the movable plate, 14, causing the cable, 16, to be gripped between the plates, 13 and 14, and the carriage is prevented from moving on the boom. When, however, the shovel is raised by the cable, J, the end of the dipper arm is moved so that because of the cam-shaped contour thereof the grip on the cable, 16, is released, permitting the carriage to move toward the end 70 of the boom. In order to return the carriage after it is dumped, I operate the power drum, 46, which by means of the engine connected therewith moves the carriage toward the mast. I may substitute for the 80 engine the counter weight and attachment hereinbefore described.

It is understood that the cable, 16, is secured at each end to the boom, B.

What I claim as my invention and desire to secure by Letters Patent, is:

1. In an excavator, the combination of a boom, a carriage mounted to travel thereon, a dipper arm hung on the carriage, a bucket carried by said arm, means for actuating said arm, and means on the carriage controlled by the movement of said arm to automatically discharge the contents of the bucket.

2. In an excavator, the combination of a boom, a carriage mounted to travel thereon, a dipper arm hung on the carriage, a bucket carried by said arm, means for actuating said arm, means controlled by said arm to automatically lock the carriage 100 to the boom, and means controlled by the movement of said arm to automatically discharge the contents of the bucket.

3. In an excavator, the combination of a boom, a carriage mounted to travel 105 thereon, a dipper arm hung on the carriage, a bucket carried by said arm, means for actuating said arm, a closure for the bucket, a trip, a connection between said trip and said closure, and a stop on the carriage in 110 the path of the trip whereby the trip will be actuated to release the closure as the dipper arm is raised.

In testimony whereof I have affixed my signature in presence of two witnesses.

STORRS M. BISHOP.
